United States Patent Office.

JESSE JOHNSON, OF WEST FALLOWFIELD TOWNSHIP, PENNSYLVANIA.

Letters Patent No. 65,391, dated June 4, 1867.

IMPROVED BOLT-CUTTER.

The Schedule referred to in these Letters Patent and making part of the same.

TO ALL WHOM IT MAY CONCERN:

Be it known that I, JESSE JOHNSON, of West Fallowfield township, in the county of Chester, and State of Pennsylvania, (my post office address being Cochranville Post Office, Chester county, Pennsylvania,) have invented a new and useful machine for the purpose of cutting off bolts and rivets made of iron or any other material, which machine is called a "Bolt and Rivet-Cutter;" and I do hereby declare that the following is a full, clear, and exact description of the construction and operation of the same, reference being had to the annexed drawings, making a part of this specification, in which—

Figure 1 is a view of the machine when forced together, as when the operation of cutting a bolt or rivet has been performed.

Figure 2 shows machine when the knives are drawn apart preparatory to receiving bolt or rivet to be cut.

Figures 3 and 4 show top and bottom plates that cover knives and frame and keep knives in proper position.

A shows stationary knife made of steel. B shows movable knife, also made of steel. Either of the knives A or B may be removed by simply unscrewing top and bottom plates, figs. 3 and 4. C shows iron frame which encases knives at the sides and ends of A, said frame being all that portion that is of red color. E and F are levers, at the ends of which, as shown, are cogs arranged to work in cogs at the sides and near the end of movable knife B, thus furnishing greater power to cut bolts and rivets than any machine patented for that purpose, there being no power lost by friction. D shows a screw in lever E to prevent the knives from striking together, in order that they may not be dulled against each other.

What I claim as my invention, and desire to secure by Letters Patent, is—

The combination of knives A and B with levers E and F, screw D, frame C, and top and bottom plates, as in figs. 3 and 4, all constructed, arranged, and employed in the manner and for the purpose shown and explained.

JESSE JOHNSON.
